UNITED STATES PATENT OFFICE.

JOSEPH WEYAND, OF GUTTENBERG, NEW JERSEY, AND WILLIAM LANG, OF NEW YORK, N. Y.

HYDRAULIC AIR-COMPRESSOR.

SPECIFICATION forming part of Letters Patent No. 415,931, dated November 26, 1889.

Application filed February 21, 1889. Serial No. 300,699. (No model.)

To all whom it may concern:

Be it known that we, JOSEPH WEYAND, of Guttenburg, in the county of Hudson and State of New Jersey, and WILLIAM LANG, of the city, county, and State of New York, have invented a new and Improved Hydraulic Air-Compressor, of which the following is a full, clear, and exact description.

Our invention relates to hydraulic air-compressors constructed to work automatically, and especially to that class of compressors employed to supply and maintain a predetermined amount of air-pressure upon liquids contained in casks or tanks stored, for instance, in the cellar of a building, to force such liquid through suitable discharge-pipes to the floor above, in order that the liquid thus raised may be conveniently drawn when and as desired through a faucet located upon the said floors.

The object of the invention is to provide an apparatus which shall possess superior advantages in point of simplicity, durability, and general efficiency over any similar apparatus or device now employed for the same purpose.

The invention consists in the novel construction and combination of the several parts, as will be hereinafter more fully set forth, and pointed out in the claims.

Reference is to be had to the accompanying drawings, forming a part of this specification, in which similar letters and figures of reference indicate corresponding parts in all the views.

Figure 1 is a central vertical section through the apparatus, illustrating the parts as in position to exert pressure. Fig. 2 is a similar section looking in an opposite direction, illustrating the parts as in position to relieve the pressure. Fig. 3 is a horizontal section on line *x x* of Fig. 1 looking downward, and Fig. 4 is a similar section on line *y y* of Fig. 2 looking upward.

In carrying out the invention the base *A*, which is cast or otherwise formed of any suitable metal, is preferably shaped to have a circular section 10, provided with a central circular cavity 11, and an essentially rectangular section 12, having elbow-tubes 13 and

14, integral with the under side, closed at the inner end. The tube 13, which is a water-inlet tube, extends horizontally parallel with one side edge of the base-section 12, and preferably transversely to an abutment with 55 the longitudinal member of the opposite parallel tube 14, which latter tube constitutes the water-outlet, and the transverse member of the outlet-tube 14 is preferably located between the base depression 11 and the corresponding member of the inlet-tube—ordinarily near the latter.

Upon the upper face of the base-section 12 a flexible washer 15 is secured by a plate 16, bearing thereon, which plate is screwed or 65 otherwise detachably secured to the base, as best illustrated in Fig. 3.

In the washer 15 and the base *A* a preferably round opening 18 is produced, leading directly into the transverse member of the 70 inlet-tube 13, which opening is adapted to receive a vertically-bored boss 19 upon the under face of the plate 16, the bore extending through the plate and the boss being of sufficient length to project about half-way into 75 the said tube 13, as best shown in Figs. 1 and 2. The wall of the lower end of the bore in the boss 19, which constitutes a valve-opening 20, is concaved, as best shown in at *a* in Fig. 1, to form a seat for a ball-valve 21. A 80 preferably larger and similar opening 22 is made in the plate, washer, and base, leading into the transverse member of the outlet-tube 14, which opening is capable of being closed at the top by a disk-valve 23. The ball-valve 85 21 is provided with a stem 24, loosely carried up through the valve-opening 20, and pivotally secured in any approved manner to a lever 25, fulcrumed at one end upon a post projected upward from the rear end of the 90 plate 16, and the disk-valve 23 is also provided with a stem, which stem is rigidly attached to the said lever. The valve-lever 25 extends longitudinally over the plate 16 between guide-lugs 25^a at the inner end of the 95 plate and downward in a curved line within the base-cavity 11, terminating over the center of the latter.

Upon the base *A* a perpendicular casing or shell *B* is bolted or otherwise secured, the 100

said shell consisting of an essentially-conical section 26 and a rectangular section 27, the side and end walls whereof are preferably inclined upward. The rectangular section extends over the conical section at the top to a point at or near the center, as shown in Figs. 1 and 2. The upper end of the rectangular section is closed by a cover-plate 28, having a capped aperture 29 over the conical section 26 of the shell, in which aperture one end of a float-rod 30 is held to slide, the opposite extremity of the rod being pivoted to one end of the valve-lever 25.

The float or rod 30 extends from top to bottom of the shell centrally through the conical section, as shown in Figs. 1 and 2, in which it will be observed that the greater portion of the rod between the ends is of larger diameter than the said ends, whereby an upper 15 and a lower shoulder 31 and 32 are formed.

Two hemispherical floats 33 and 34 are held to slide upon the rod 30. The lower float is limited in its upward movement by the lower shoulder 32, which it cannot pass. The upper 25 float, however, is free to rise upward until it contacts with the inner upper surface of the conical surface of the shell, as shown in Fig. 2. The contour of the shell at this point is such as to neatly receive the upper float.

30 A nipple 35, having an exteriorly-threaded flanged base, is formed integral with the upper surface of the cover-plate at or near the outer end, which nipple is covered by a flexible jacket 36, provided with a slit at the top 35 over the bore of the nipple, as best shown in Fig. 1. The jacket 36 is surrounded by a cap 37, having an integral outlet-tube 38, which cap is held in position by a lock-nut 39, swiveled upon the nipple and screwed upon the 40 flange of the same. A channel 40 intersects the bore of the nipple, which channel extends longitudinally rearward and downward through the bottom of the cover-plate 28. A second channel 41 is produced in the front 45 end of the cover-plate, affording direct communication with the interior of the shell B and the atmosphere surrounding the same.

The inner mouths of the channels 40 and 41 are controlled by disk-valves 42 and 43, secured to an arm 44, fulcrumed near the outer end beneath the cover-plate, the inner end of said arm being slotted to receive the upper end of the float-rod capable of being acted upon by the shoulder 31 of said rod. 50 The valves 42 and 43 are located one at each side of the fulcrum-point of the arm 44, whereby when one channel—40, for instance—is closed the other channel 41 will be open.

We desire it to be distinctly understood 55 that although specific construction has been shown and described other equivalent construction may be employed without departing from the spirit of the invention.

In operation, the floats being one upon the 60 other in the bottom of the shell B, the disk-valve 23 is closed over the outlet-opening 22, and the inlet-opening 20 is opened. Thus

the water entering through the inlet-tube 13 passes up through the valve-opening 20 into the interior of the shell, whereupon the two 70 floats 33 and 34 are elevated, thereby creating an air-pressure within the shell, which, bearing downward upon the disk-valve 23, suffices to retain the same in a closed position. The lower float 34 rises only until it strikes the 75 shoulder 32 of the rod 30, but the upper float 33 continues to rise with the incoming water, and the air forced out from the shell by the entrance of the water finds an escape through the channel 40, which is open, as shown in 80 Fig. 1; from thence through the nipple and out through the slit in the jacket into the cap 37, and from the cap the compressed air finds an exit through the outlet-tube 38, which tube is in communication with a barrel 85 or cask containing the beer or other fluid. When the upper float 34 is carried by the water to the position illustrated in Fig. 2—namely in contact with the upper inner surface of the conical section of the shell—the 90 inner end of the arm 44, carrying the valves 42 and 33, is elevated sufficiently to close the mouth of the channel 40 and open the inner mouth of the outer channel 41. Through this channel the compressed air not needed 95 in the manipulation of the fluid escapes, and as the air escapes pressure is removed from the disk-valve 23, and the lower float, bearing upward against the shoulder 32, raises the rod 30, thereby causing the ball-valve 21 to close 100 the inlet-opening 20, which movement also raises the disk-valve 23, whereupon the water finds a speedy and free exit through the outlet-tube 14. As the level of the water nears the base of the shell the upper float finds a 105 seat upon the lower float, and as the water leaves the said upper float the weight of the latter causes the lower float to bear down a slight distance in the direction of the valve-lever, the length of the lower reduction of 110 the float-rod being so calculated that when the lower float is in this position the upper surface will be removed some distance from the lower rod-shoulder 32. In the further operation, when the level of the water practically 115 reaches the level of the base, the combined weight of the floats is such that they will drop heavily downward and force the free end of the lever instantly deep in the cavity 120 11, whereby the outlet-valve is closed and the inlet-valve opened. The movement of the lever is so precipitated by the action of the incoming water as soon as the ball-valve is unseated in the slightest degree that the sudden violent downward movement of the floats 125 and lever creates quite a loud report.

The cavity 11 is always more or less filled with water, consequently the floats rebound somewhat after striking the same, but the distance between the lower float and the shoulder is such that even at the greatest rebound the two will not contact; thus the lever remains passive. Any well-known or approved form of regulator may be employed in

connection with the compressor above described.

Having thus described our invention, we claim as new and desire to secure by Letters 5 Patent—

1. The combination, with a shell having water inlet and outlet openings, a lever pivoted within the shell, two valves controlling said openings and connected with said lever, 10 and a vertical rod connected at its lower end with the said lever and provided with vertically-sliding floats, the lower float having a limited upward movement on the rod to raise it, of air delivery and waste channels in the 15 upper end of the shell, a lever provided with valves for both channels and extending into the path of the upper float, substantially as set forth.

2. The combination, with a shell provided 20 with water inlet and outlet openings, a lever pivoted within the shell, valves attached to said lever and controlling said openings, a vertical rod pivotally connected at its lower end to said lever and floats movable up and 25 down upon said rod, of a cap-plate provided with air delivery and waste channels, a nipple forming a continuation of the delivery-channel, a flexible apertured jacket covering the nipple, and an arm fulcrumed beneath 30 the cap-plate, carrying valves controlling the channels and capable of contact with the upper one of the said floats, substantially as shown and described.

3. The combination, with a shell provided 35 with water inlet and outlet openings, a lever pivoted within the shell, valves attached to said lever and controlling said openings, a vertical rod pivoted to one end of the valve-lever, and floats movable up and down upon the said 40 rod, of a cap-plate provided with air delivery and waste channels, a nipple forming a continuation of the delivery-channel, a flexible apertured jacket covering the nipple, a nozzled cap surrounding said jacket, an arm fulcrumed beneath the cap-plate capable of 45 sliding upon the float-rod in the path of the upper float, and valves secured to the said arm capable of controlling said channels, all combined for operation substantially as 50 shown and described.

4. The combination, with a shell having a conical and a rectangular vertical section and provided with water outlet and inlet openings in the base, a lever fulcrumed at one

end upon the inner face of the base, a downwardly-opening ball-valve pivoted to the lever controlling the inlet-opening, and a disk-valve secured to the lever controlling the outlet-opening and closing downwardly, of a vertical rod pivoted to the inner end of the 60 lever within the conical section of the shell provided with a shoulder near the lower end, hemispherical floats held to slide upon the said rod, the lower one of which is adapted to engage said shoulder and raise the rod, a cap-plate provided with air delivery and waste channels, an arm fulcrumed beneath the cap-plate capable of movement at one end upon the float-rod and of contact with the upper float, and valves secured to the arm capable 65 of controlling the channels in the cap-plate, 70 all combined for operation substantially as shown and described.

5. The combination, with a shell having a conical and a rectangular vertical section and 75 provided with water outlet and inlet openings in the base, a lever fulcrumed at one end upon the inner surface of the base, a ball-valve pivoted to the lever controlling the inlet-opening, and a disk-valve rigidly secured 80 to the lever controlling the outlet-opening, of a rod extending vertically upward through the conical section of the shell, pivoted to the inner extremity of the valve-lever, and provided with a shoulder near each extremity, 85 two hemispherical floats held to slide upon the said rod, the movement of the lower float being limited by the lower shoulder of the rod, and the upper float capable of ascension to the top of the rod, a cap-plate covering the 90 top of the shell provided with air delivery and waste channels, a flexible valve attached at one end of the delivery-channel, an arm fulcrumed beneath the cap-plate apertured to receive the upper end of the float-rod and 95 capable of bearing upon the upper shoulder of the same, and disk-valves secured to the upper face of the said arm at each side of the fulcrum-point capable of closing the inner mouth of the delivery and waste channels, 100 all combined for operation substantially as and for the purpose specified.
